COMBINED COMB AND BRUSH

Louis L. Love, Philadelphia, Pa.

Application October 23, 1948, Serial No. 149,255

Term of patent 14 years

(Cl. D86—10)

To all whom it may concern:

Be it known that I, Louis L. Love, a citizen of the United States, residing at Philadelphia, in the county of Philadelphia and State of Pennsylvania, have invented a new, original, and ornamental Design for a Combined Comb and Brush, of which the following is a specification, reference being had to the accompanying drawing, forming a part thereof.

In the drawing:

Fig. 1 is a front elevational view of a combined comb and brush, showing my new design;

Fig. 2 is a top plan view;

Fig. 3 is a side elevational view looking at the brush end;

Fig. 4 is a side elevational view looking at the handle end of the same.

I claim:

The ornamental design for a combined comb and brush, as shown.

LOUIS L. LOVE.
